(57) **CLAIM**

The ornamental design for an item holder connected to a line dispenser, as substantially shown and described.

DESCRIPTION

FIG. 1 is a front perspective view of the novel item holder when connected in abutting relation to a line dispenser; FIG. 2 is a front perspective view of the novel item holder when spaced apart from said line dispenser; FIG. 3 is a rear perspective view of the novel item holder when connected in abutting relation to said line dispenser; FIG. 4 is a rear perspective view of the novel item holder when spaced apart from said line dispenser; FIG. 5 is a front perspective view of the novel item holder when connected in abutting relation to said line dispenser and when a lighter item is held in said holder; FIG. 6 is a rear perspective view of the novel item holder when connected in abutting relation to said line dispenser and when said lighter item is held in said holder; FIG. 7 is a side elevational view of the novel item holder when connected in abutting relation to said line dispenser; and, FIG. 8 is a top plan view of the novel item holder when connected in abutting relation to said line dispenser. The broken line showing of environment in the drawings is included for the purpose of illustration only and forms no part of the claimed design.
